 Joseph J. Mayo(57) **CLAIM**

The ornamental design for a cane chair, as shown and described.

DESCRIPTION

FIG. 1 is an upper front perspective view of a cane chair. FIG. 2 is an upper back perspective view of the cane chair as shown in FIG. 1.

FIG. 3 is a front view of the cane chair as shown in FIG. 1. FIG. 4 is a back view of the cane chair as shown in FIG. 1. FIG. 5 is a right side view of the cane chair as shown in FIG. 1, the left side view being a mirror image of the right side view.

FIG. 6 is a bottom view of the cane chair as shown in FIG. 1; and,

FIG. 7 is a top view of the cane chair as shown in FIG. 1. The broken lines shown in the figures illustrate environment that forms no part of the claimed design.
